UNITED STATES PATENT OFFICE.

JAMES BUCKLEY, OF LIVERPOOL, ENGLAND, ASSIGNOR OF TWO-THIRDS
TO JOHN HENRY BUCKLEY, OF CHEW MOOR, AND ELIJAH ASHWORTH,
OF MANCHESTER, ENGLAND.

SPINNING-MACHINE.

SPECIFICATION forming part of Letters Patent No. 632,172, dated August 29, 1899.

Application filed December 20, 1897. Serial No. 662,715. (No model.)

To all whom it may concern:

Be it known that I, JAMES BUCKLEY, retired cotton-mill manager, a subject of the Queen of Great Britain and Ireland, residing at 51 5 Mount Pleasant, Liverpool, in the county of Lancaster, England, have invented Improvements in or Relating to Spinning Machinery, which are also applicable to doubling machinery, of which the following is a specification.

10 This invention refers to improvements in or relating to machinery, such as ring-frames and others, for spinning and doubling cotton, wool, and other fibrous materials, and has for its object the making of firmer and more 15 reliable yarn, free from soft places and less waste than hitherto. The invention is equally applicable to machines for spinning on the bare spindle or bobbin.

20 To carry my invention into effect, when commencing the winding of cops the drawing-rollers are driven at a constant speed, but as the cop-bottoms are being formed I drive the drawing-rollers at a variable speed. When the cop-bottoms are formed, the maximum 25 speed is imparted to the drawing-rollers when commencing the "chase" and is gradually reduced to a minimum as the end of the chase or the bare spindle is reached. By these means the drawing-rollers deliver the greatest 30 amount of yarn when it is most required—viz., when winding on the thickest portion of the cop-nose, the supply being gradually diminished as the yarn is wound on the thinner portion of the cop-nose.

35 In order that my invention may be more fully understood, I have attached hereto four sheets of explanatory drawings of the mechanism whereby my object is attained.

40 Figure 1 is so much of a front elevation of a ring-spinning or doubling frame as is necessary to illustrate my invention. Fig. 2 is a plan of same. Fig. 3 is an end elevation of Fig. 1, looking in the direction of the arrow a. Fig. 4 is sectional plan through the line 45 A B, Fig. 3. Fig. 4^a is a side elevation of a mutilated worm-wheel constructed to allow the regulator to drop out of gear automatically when the cop-bottom is formed. Fig. 4^b is a view of a detail. Fig. 5 is a plan view

of the main driving-shaft and connections. 50 Fig. 6 is an end view of the heart-cam and dies. Fig. 7 is a side view of Fig. 6. Fig. 8 is a sectional elevation of Fig. 1 on the line C D, looking in the direction of the arrow b. Fig. 9 is a back elevation looking in the direction of the arrow c, Fig. 4. Figs. 10 and 11 are detail views of the clutch mechanism. Figs. 12 and 13 show the method of driving the drawing or delivery rollers. Fig. 14 shows a cop-nose, indicating the winding of 60 the yarn on the cop-nose when traveling downward.

In all the figures the same numerals are employed to indicate corresponding parts.

The frame end is marked 1, the ring-rail 2, 65 the footstep-rail 3, the roller-beam 4, the drawing or press rollers 5, the tin driving-cylinders 6, the main driving-shaft 7, and the usual fast and loose pulleys 8.

In the frame end 1 of the machine I mount 70 a shaft 9, upon which is mounted a spur-wheel 10. The spur-wheel 10 is provided with a slot 11, in which slides a diamond or block 12, carrying a stud 13, which is secured to a stud-wheel 14. The stud-wheel 14 is 75 formed with spur-wheel teeth and is carried on a stud 15, secured to the upper end of a radial arm 16. The other end of the stud 15 is fixed to a sliding block 17, carried in a slot 18, formed in the bar 19. The bar 19 is secured to the frame 1 by end brackets 20. To the block 17 is attached a nut 21, screw-threaded to receive a threaded regulating-spindle 22, mounted in bearings 23, carried by the bar 19. The radial arm 16 carries a 80 pin or axis 24, engaging with a slot 25, formed in the arm 16. The radial arm 16 is secured to a slotted lever 32 by means of a stud 33^x, as shown in Figs. 3 and 8. On the pin 24 are loosely mounted a spur-pinion 26 85 and spur-wheel 27, connected together, the pinion 26 gearing with the stud-wheel 14 and the spur-wheel 27 gearing with a pinion 28, loosely mounted on the stud 29. Upon the stud 29 are also loosely mounted spur-wheels 30 30^x, (see Figs. 1, 3, and 5,) gearing with spur-pinions 31 31^x on the main driving-shaft 7. (See Fig. 5.) The pinion 28 and spur-

wheels 30 30^X are connected so as to revolve together. The spur-pinions 31 31^X are mounted loosely upon the shaft 7 and are provided with the clutch-boxes 32 and 33, respectively, 5 which are operated by the forks 34 on the sliding bar 35, mounted in the bracket 36, secured to the frame of the machine. The sliding parts of the clutch-boxes 32 33 are driven by the keys or feathers 37 on the shaft 7. When the machine or frame is set in motion on the commencement or formation of the cops and when the spindles or bobbins are bare, the slotted wheel 10 and stud-wheel 14 are concentric to each other, as shown in 10 Figs. 1, 2, 3, 4, 5, and 8, and the clutch-box 32 is in gear. The spur-pinion 31 has one or more teeth less than the spur-pinion 31^X for the purpose of reducing the speed of the drawing-rollers when commencing to spin on the 15 bare spindle, so as to prevent soft yarn. The sliding clutch half of the clutch-box 32 is held in gear by the pin 38, mounted in the slide-fixing 36. The pin 38 drops into a notch in the edge of the sliding bar 35, by which it 20 is held until a sufficient portion of the cop has been spun. When the driving-shaft 7 is rotated to drive the machine or frame, the 25 gearing 31, 30, 28, 27, and 26 are operated to drive the stud-wheel 14, which drives the slot-wheel 10 by means of the stud 13 and diamond or block 12 in the slot 11.

To obtain the variable speed of the drawing-rollers, the stud-wheel 14 must be arranged eccentrically to the slot-wheel 10, 30 which is gradually effected during the formation of the cop-bottoms and in the following manner: The rotation of the slot-wheel 10 operates the shaft 9 and worm 39, the latter 35 gearing into the worm-wheel 40 on the shaft 41 in the fixings or bearings 42. On the shaft 41 is fixed the worm 43, gearing into the worm-wheel 44 on the shaft 45. The shaft 45 is mounted in the bearings 46 and is fitted with the bevel-wheel 47, gearing into the bevel-wheel 48 on the spindle 22, by which the latter 40 is driven to regulate the position of the stud 14 and place it gradually in an eccentric position to the slot-wheel 10 until the cop-bottom has been formed. When the cop-bottom 45 has been formed, the worm-wheel 44 will 50 have been rotated to bring the part devoid of teeth (shown in Fig. 4^a) under the worm 43, by which the regulation of the stud-wheel 14 will cease. The requisite degree of eccentricity of the stud-wheel 14 to the slot-wheel 10 has then been attained. The shaft 45 is 55 provided with the key or feather 49 to allow of the worm-wheel 44 being slid out of gear when resetting the stud-wheel 14 into a concentric position with the slot-wheel 10 for the next set of cops. Before this greatest degree of eccentricity is, however, attained and at a period when the cop-bottoms are about half formed it is desirable to increase the speed of 60 delivery of the yarn owing to the increasing size of the cop-bottoms. This is effected by 65 means of the pivoted lever 51, which is op-

erated by the cam 50 on the shaft 41. The pivoted lever 51 lifts the pin 38 from the sliding frame 36 by means of the chain 52. Immediately the slide-bar 35 is released from the pin 38 it is slid by the action of the spring 54 in such a manner as to pull the clutch-box 32 out of gear with the pinion 31 and put the clutch-box 33 in gear with the pinion 31^X. (See Figs. 10 and 11.) As has already been mentioned, the pinion 31^X is provided with one or more teeth in excess of the pinion 31, and thus the requisite slight increase of speed of the drawing-rollers through the intermediate gearing is attained. 70 75 80

It will be understood from the foregoing description that although the slot-wheel 10 revolves upon the shaft 9, yet the stud-wheel 14, carried by the radial arm 16, by which the slot-wheel 10 is driven, has been gradually shifted during the formation of the cop-bottom from a concentric to an eccentric position relatively to the slot-wheel 10. Therefore as the stud-wheel 14 revolves eccentrically to the slot-wheel 10 the sliding of the diamond or block 12 within the slot 11 creates a differential speed of the slot-wheel 10, although the speed of the stud-wheel 14 is constant. The maximum speed of the slot-wheel 10 is attained when the block 12 is moved by the stud-wheel 14 to the position in the slot 11 nearest to the center of the slot-wheel 10 and gradually approaches its minimum as the block 12 is moved outward toward the periphery of the slot-wheel 10. The drawing-rollers 5 are driven from the slot-wheel 10, and therefore receive a variable speed. This variable speed is arranged to be commenced at a maximum when commencing the chase 95 of the cop-nose and is gradually reduced to a minimum when winding on the bare spindle at the end of the chase. The drawing-rollers therefore deliver the greatest amount of yarn at the time when it is required—viz., when 100 winding on the thickest portion of the cop-nose—gradually reducing the supply of yarn as the bare spindle is approached. The apparatus thus effects a more regular twist and 105 more uniform yarn than hitherto, giving the same number of turns or twist to the yarn per inch both at the thickest and at any other point of the chase. 110 115

The drawing-rollers 5 are driven from the slot-wheel 10 in the usual and well-known 120 manner, as indicated more particularly in Figs. 12 and 13, Sheet 4. A bracket 55 carries a stud 56, upon which is mounted two pinions 57 and 58^X, secured together. (See Fig. 3.) The pinion 57 is driven by the slot-wheel 10, and by means of the connected pinion 58^X drives a pinion 59^X, secured upon the axis 60^X of the front drawing-rollers. Upon the axis 60^X is secured a pinion 61^X, gearing with a pinion 62^X, secured upon a stud 63, 125 which also carries a pinion 64^X, gearing with and imparting motion to a pinion 65^X on the axis of the back drawing-rollers. The middle 130 drawing-rollers are driven by means of a pin-

ion 66^x on the axis of the back drawing-rollers, which gears through an intermediate wheel with a pinion 67^x, keyed on the axis of the middle drawing-rollers, being employed 5 to give them the required opposite direction of motion.

The coppering-motion is operated and regulated by the movements of the slot-wheel 10 on the shaft 9. On the shaft 9 is mounted a 10 bevel-wheel 58, gearing with a bevel-wheel 59 on the inclined shaft 60. (See Figs. 3 and 8.) The shaft 60 is also provided with a bevel-wheel 61, gearing with the bevel-wheel 62, mounted upon the heart-cam shaft 63, thereby 15 communicating the requisite motion to the heart-cam shaft. To assimilate the winding of the ring-frame to that of the mule and thereby render the cop-nose less liable to pull to waste, I provide, in conjunction with the 20 ordinary bowl, two dies or followers 65 to work with the heart-cam 64, as shown in Figs. 6 and 7, by which the same will reduce friction and allow of a speedy change when winding on the cop-nose. The dies 64 are 25 mounted on the coppering-lever 66 on each side of the ordinary bowl 67. The heart-cam 64 is increased in thickness at the end to operate on the dies 65, but is of the ordinary thickness in the remaining part to operate on 30 the bowl 67. As shown in Fig. 7, the heart-cam 64 is revolving in the direction of the arrow. The thickened portion of the heart-cam is shown from *a*^x to *b*^x, and from this portion *a* to *b* the heart-cam leaves the bowl 35 67 and slides upon the dies 65. In the position shown in Figs. 6 and 7 the point of reversal of the ring-rail 2 has been reached. The thickened portion of the heart-cam 64 drops rapidly down the side of the dies 65 40 upon the bowl 67, by which means a rapid reversal of the ring-rail is obtained and soft cop-nose avoided. This arrangement produces winding on the cop-nose when traveling downward, as shown in Fig. 14, and is a 45 facsimile of that produced on the ordinary spinning-mule. The lever 66 is connected to the pulley 68 on the shaft 69 by means of a chain 70. The shaft 69 is supported in bearings 71, attached to the frame end 1. On the 50 shaft 69 is fixed the pulley 72, to which is secured the chain 73 to connect it with the quadrant 74 on the shaft 75. The shaft 75 is fitted with the lever 76, to which is pivoted the upright 77, secured to the coppering-rail 2. The 55 upright 77 is mounted in the bearings 78 in the bolster-rail 3. It must be understood that this method of imparting the requisite motion to the ring-rail through the coppering-lever and

quadrant is old and forms no part of my invention.

I claim—

1. In combination, the drawing-rollers, the coppering-motion, a drive-shaft and means intermediate of said rollers and coppering-motion and the driving-shaft for imparting a differential motion, consisting of two wheels having a sliding connection between them, one of said wheels having geared connections with the drive-shaft, and the other being in connection with the drawing-rollers and coppering-motion and means for automatically adjusting one of said wheels in relation to the other to change from a concentric to an eccentric relation, substantially as described.

2. In combination, the drawing-rollers, the coppering-motion, a drive-shaft and means intermediate of said rollers and coppering-motion and the driving-shaft for imparting a differential motion, consisting of two wheels having a sliding connection between them, one of said wheels having geared connections with the drive-shaft, and the other being in connection with the drawing-rollers and coppering-motion, means for automatically adjusting one of said wheels in relation to the other to change from a concentric to an eccentric relation, and clutch-boxes on the drive-shaft with means for automatically changing them, substantially as described.

3. In combination in a coppering-motion, the coppering-lever, the two dies 65, the intermediate roller and the heart-shaped cam having a thickened portion to engage the dies and a thin portion to engage the roller, substantially as described.

4. In combination, the drawing-rollers and coppering-motion, the driving-shaft, the stud-wheel 14, the gearing between the same and the driving-shaft, the slot-wheel 10 having a sliding block connected with the stud-wheel 14, the gearing between the slot-wheel and drawing-rollers, the geared connections between the slot-wheel and the coppering-lever, the movable bearing for the stud-wheel 14 and means for automatically operating the same consisting of the screw-shaft 22, the shaft 9 of the slot-wheel 10 and the gearing between the shaft 9 and the shaft 22 substantially as described.

In witness whereof I have hereunto set my hand in presence of two witnesses.

JAMES BUCKLEY.
